(57) **CLAIM**

The ornamental design for a buffer receptacle, as shown and described.

DESCRIPTION

FIG. 1 is a rear, top, and left perspective view of a first embodiment of a buffer receptacle showing our new design;

FIG. 2 is a front, top, and left perspective view thereof;

FIG. 3 is a rear elevational view thereof;

FIG. 4 is a front elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is a rear, bottom, and right perspective view thereof;

FIG. 10 is a front, bottom, and right perspective view thereof;

FIG. 11 is a rear, top, and left perspective view of a second embodiment of a buffer receptacle;

FIG. 12 is a front, top, and left perspective view thereof;

FIG. 13 is a rear elevational view thereof;

FIG. 14 is a front elevational view thereof;

FIG. 15 is a right side elevational view thereof;

FIG. 16 is a left side elevational view thereof;

FIG. 17 is a top plan view thereof;

FIG. 18 is a bottom plan view thereof;

FIG. 19 is a rear, bottom, and right perspective view thereof;

FIG. 20 is a front, bottom, and right perspective view thereof;

FIG. 21 is a rear, top, and left perspective view of a third embodiment of a buffer receptacle;

FIG. 22 is a front, top, and left perspective view thereof;

FIG. 23 is a rear elevational view thereof;

FIG. 24 is a front elevational view thereof;

FIG. 25 is a right side elevational view thereof;

(Continued)

FIG. 26 is a left side elevational view thereof;
FIG. 27 is a top plan view thereof;
FIG. 28 is a bottom plan view thereof;
FIG. 29 is a rear, bottom, and right perspective view thereof;
and,
FIG. 30 is a front, bottom, and right perspective view thereof.
The broken lines shown in the drawings illustrate portions of the buffer receptacle that form no part of the claimed design.
